UNITED STATES PATENT OFFICE

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS

BRAKE BEAM SUPPORT

Application filed February 19, 1931. Serial No. 517,063.

This invention relates to railway rolling stock and consists particularly in a novel supporting means for brake beams.

In clasp brake arrangements for car trucks, the braking force is transmitted to each brake beam through either one or two brake levers according to maximum load requirements. In the first case, the lever is pivotally secured to a fulcrum centrally located 10 on the brake beam and in the second case, the levers are connected to the outer portions of the beam. Beams of I section are generally used and a short fulcrum arm is usually provided thereon.

15 The beams are normally supported at each end by hangers depending from suitable brackets on the truck and hooked through the brake heads, but additional support is desirable to prevent the beam from falling to 20 the track in case one, or both, of the hangers is broken, as well as to prevent the tilting of the beam. Fourth point supports are commonly used for the above purpose; that is, 25 two additional supports are provided, one under each outer end of the beam. The supports are usually secured to the spring plank and each support engages a suitable projection or chair on the brake beam.

The main object of my invention is to provide 30 a novel chair particularly adapted for use in connection with fourth point supports. I attain this object in the structure illustrated in the accompanying drawing in which

35 Figure 1 is a fragmentary top view of a truck embodying my invention and showing the brake lever in section.

Figure 2 is a side view of the same with 40 some of the parts sectioned for clearer illustration.

Figure 3 is a detail top view of parts showing a modification of the invention.

Figure 4 is a side view of the same.

The truck may be of any suitable type, but is shown as composed of side frames including pedestals 1 and an intermediate recess 2 for receiving a spring plank 3 and the end of bolster 4 which rests upon springs (not shown). A brake beam 5 of I section mounts 50 a brake head 6 at each end, the brake head

being supported directly from the truck frame by hangers 7.

A fulcrum arm 8, riveted to the brake beam near each end thereof, is bifurcated for receiving a brake lever 9, pivotally secured 55 to the fulcrum by pin 10. In Figures 1 and 2, I show a support chair 11 projecting downwardly from the end of fulcrum 8 and formed integrally therewith. The chair bears directly against a guard, guide, or support strap 12 which is carried by the spring plank 3 by means of a bracket 13.

In Figures 3 and 4, the chair 14 is formed separately and has bifurcations 14a in the upper part thereof which embrace the bifurcated end of arm 16 and are secured thereto by a pin 17. Pin 17 also extends through lever 15 and serves to pivotally connect the same with the fulcrum arm. Any other suitable type of pivotal connection between the chair, arm and lever may be utilized if desired. The operation and function of the modified device is the same as that of the form shown in Figures 1 and 2.

It will be seen that my novel supporting 75 chair is located substantially in line with the brake lever and somewhat forward from the brake beam itself, thus preventing the tilting of the beam under influence of wheel rotation during braking, and of the preponderance of weight of beam and parts in front of pivoting point of brake hanger in brake head, and also providing an effective and easily assembled chair, strut, and lever structure.

85 My invention is primarily adapted for use in connection with fourth point supports of bar type brake beams, but it will be understood that the principles thereof are equally applicable wherever the brake lever engages the end of a strut or fulcrum arm. Furthermore, the support itself need not necessarily be suspended from the spring plank, but may be secured to any other convenient portion of the truck frame. These and other modifications may be made in the details of the structure disclosed without departing from the spirit of the invention and I contemplate the exclusive use of all such variations as come 90 within the scope of my claims.

I claim:

1. A fulcrum arm for a brake beam having an end portion arranged for pivotal connection with a brake lever and having a supporting chair depending from said portion.
5
2. A fulcrum arm for a brake beam having a bifurcated forward portion for pivotally mounting the end of a brake lever, and having a supporting chair depending from said portion and integral therewith.
10
3. A fulcrum arm for a brake beam comprising a portion adapted to be secured to the brake beam, and a portion disposed at an angle to said first mentioned portion and forming a supporting chair for the beam, the intersection of said portions being arranged to pivotally mount the end of a brake lever.
15
4. A supporting chair for a brake beam having a support engaging surface, and a portion adapted to engage intersecting ends of a brake beam fulcrum and a brake lever.
20
5. A supporting chair for a brake beam having a lower support engaging surface and an upper bifurcated portion adapted to receive a brake lever and a brake beam fulcrum between the bifurcations thereof.
25
6. In combination, a brake beam, a guard, guide or support member below said beam, a brake lever, a fulcrum arm projecting from said beam and having a pivotal connection with said lever, and a support chair depending from said pivotal connection and resting upon said guard, guide, or support member.
30
7. In combination, a brake beam, a guard, guide or support member below said beam, a brake lever, a fulcrum arm projecting from said beam and having bifurcations disposed on opposite sides of said lever, a supporting chair having a portion overlapping said bifurcations and said lever, and a pin extending through said portion, bifurcations, and lever and pivotally securing the same together.
35

In testimony whereof I hereunto affix my signature this 16 day of February, 1931.

45 EDWIN G. BUSSE.
